Inventor:
Alfred K. Miller,

By his attorney

UNITED STATES PATENT OFFICE.

ALFRED K. MILLER, OF LOS ANGELES, CALIFORNIA.

TONE ARM.

Application filed February 5, 1921. Serial No. 442,641.

To all whom it may concern:

Be it known that I, ALFRED K. MILLER, a citizen of the United States, residing at Los Angeles, county of Los Angeles, State 5 of California, have invented new and useful Improvements in Tone Arms, of which the following is a specification.

This invention relates to devices and apparatus of the general character that is used 10 as, and is generally known as, the tone arm of a phonograph mechanism; so, for the purpose of clearly describing and illustrating my invention, I shall consider a specific form of the invention which is particularly 15 designed as a tone arm for a phonograph, but it will be distinctly understood that I do not thereby limit my invention to such particular use. In its broader aspects my invention may be considered to be a sound 20 transmitting and modifying apparatus.

Considering thus my invention as applied to tone arms (without any implied limitation of the invention thereto) it may be stated preliminarily that one of the objects 25 of the invention is to provide a tone arm construction that will amplify sounds coming from a phonograph reproducer; will amplify and expand the sound without introducing into it foreign vibrations of any 30 objectionable character; will transmit the sound from the reproducer in its original purity; and will, without materially altering the character or quality of the tones produced by the reproducer, somewhat qualify 35 those tones, so as to eliminate from those tones certain somewhat undesirable features. This elimination of certain undesirable 40 features or qualities of the tone coming from the reproducer applies more particularly to ordinary reproducers than to my reproducer of the character shown in the accompanying drawings. In an ordinary reproducer as used in present phonographs, there is always a tendency for certain tones or sound 45 to blare out; that is, to be reproduced with such force and volume as to practically drown out the accompanying sounds. This objectionable feature has been to a very large extent eliminated in my reproducer; but the 50 tone arm itself has, as will be explained, the quality of "covering" tones which would otherwise be produced in a blaring fashion.

There are other objects of the invention; but they, together with the foregoing objects, will be better understood from the following detailed description of specific forms

of my invention, reference for that purpose being had to the accompanying drawings, in which:

Fig. 1 is a plan of my improved tone arm, 60 showing a reproducer in connection therewith and showing the connection of a tone arm of the phonograph; Fig. 2 is a horizontal longitudinal section of the same; Fig. 3 is a similar horizontal longitudinal section 65 showing a slightly modified arrangement; Fig. 4 is a section showing my improved reproducer which is here shown in connection with the tone arm, and Fig. 5 is an enlarged detail section taken as indicated by 70 line 5—5 on Fig. 2.

In the drawings the numeral 10 may generally designate the upper end of the horn of the instrument, this upper end of the horn being provided with a horizontally 75 swinging swivel which turns on the center pivot 11. To provide arrangements so that the reproducer may follow the vertical undulations or inaccuracies of a phonograph record, I prefer in my construction to place 80 the freely vertically movable joint or section at the rear of the tone arm rather than between the tone arm and the reproducer; so that the reproducer is mounted more directly, and without the interposition of a 85 number of movable joints, or any loosely movable joint, in its connection with the forward end of the tone arm. Accordingly, in my present arrangement the upper end of the horn, or the swivel thereof, has a cup-shaped 90 flange 12 within which a collar 13 fits somewhat loosely, the collar being mounted in the flange on a pair of pivots 14, as is clearly illustrated. These pivots are on a horizontal 95 pivot line, so that the tone arm, whose rear end is mounted in the collar 13, may raise and lower slightly. Between the end of the collar 13 and the flange 12 I interpose a washer of some suitable soft material as at 15, such as soft felt. This washer substantially fills up the otherwise open space at that point, at the same time is soft enough to allow the slight tilting motion necessary 100 for the reproducer to raise and lower in following the vertical undulations which are 105 usually present in any ordinary phonograph record, due to such phonograph records not being absolutely true and flat disks, or due to the carrier table not being absolutely true.

Referring first to Figs. 1, 2 and 5, it will 110 be seen that the tone arm proper comprises an outer cylindrical shell 20, comparatively

long. This shell is preferably rather heavily walled; and I find that ordinary brass tubing, with rather heavy walls, is suitable for the purpose. It is not intended that the 5 walls of this shell be vibratory or resonant; but it is rather intended that they be solid. Shell 20 is mounted in the collar 13 at its rear end. At its forward end it receives and supports the forward end of interior-sound 10 modifying member 21 and also supports the reproducer R. In the form shown in Figs. 1, 2 and 5 the elbow 22, upon which the reproducer R is mounted, extends into the forward end of the hollow sound modifying member 21 and is rotatable therein, from the 15 position indicated in Figs. 1 and 2 to a position where the elbow extends upwardly rather than horizontally. This swinging movement is limited by a pin and slot arrangement, as indicated at 23, so that the reproducer may be rotated around the horizontal longitudinal axis of the tone arm to an angle of about 90°. This relative movement 20 of the reproducer allows the reproducer to be raised from a record for changing records and for changing needles. The horizontal arm of elbow 22 fits in the forward end of hollow sound modifier 21 with a fairly tight friction, so that although it may be turned 25 by hand from one position to the other, there is no looseness at the point. The reproducer, mounted upon the elbow 22, fits upon that elbow with a fairly tight joint, so that there is no looseness at that point. Thus 30 as will be referred to hereinafter, there are no loose joints between the reproducer, or between the vibrating sound producing parts of the reproducer, and the forward end of the tone arm and sound modifying member 21.

The sound waves which pass through elbow 22 from the reproducer are delivered 35 into the forward end of hollow sound modifying member 21. This resonating member is, in the preferred form of construction shown in the drawings and herein explained, supported at its forward end only in exterior shell 20. Exterior shell 20 is preferably cylindrical; that is it is preferably of the same 40 size throughout and preferably circular in cross section; although its cross sectional configuration can be made other than circular. The sound modifying member 21 is also, correspondingly, circular in cross section, so 45 that it may be arranged concentrically with relation to shell 20. Sound modifying member 21 may preferably be constructed of fibre, wood, or bakelite or some suitable material of like nature; suitable to be resonantly vibratory without having the characteristic metallic quality of a thin metallic vibratory tube or tongue or the like. Thus, 50 for instance, I make the sound modifier 21 of a suitable hard fibre, or hard wood. 55 throughout most of its length it has a rela-

tively thin cylindrical wall 25, which wall is, at the forward end at 26, expanded so as to fit tightly into shell 20. Throughout part of its length, preferably through most of its length, the wall 25 has one or more slots 70 27 cut through it. For instance it may have two opposite longitudinal slots as shown in the drawing. These slots may or may not extend to the rear end of the tube; but in my present preferred construction I prefer to have them stop somewhat short of the rear end of the sound modifying tube; and the rear end of the resonating tube is choked down somewhat as is illustrated at 28. Other than this slight closure or choke the 75 hollow interior of the sound modifying tube is of the same size throughout its length. Also, preferably, although not necessarily, the exterior surface of the sound modifying tube wall, is truly cylindrical; so that the 80 annular space between the sound modifying tube and shell 20 is of the same size throughout its length.

Without attempting to limit myself to the 85 particular proportions and conformations herein shown and described, I may say that, as a typical instance, I obtain very good results from a device built substantially in accordance with the drawings herewith; which drawings are approximately to proportionate scale; and the length of shell 20 being about six inches and its outside diameter one and one-half inches and the thickness of its wall one-sixteenth of an inch; the exterior diameter of the sound modifying tube being one and one-eighth inches and the thickness of the sound modifying tube wall being about one-sixteenth of an inch; the sound modifying tube being constructed of what is known as hard fibre. Its length is about five and one-half inches. The inside diameter of the choked end is about fifteen-sixteenths of an inch.

In actual operation I find that a tone arm 90 constructed in accordance with my present invention gives very markedly improved results. The sound is transmitted without intrusion of undesirable foreign sounds. Amplification is caused by the tubular sound modifying member. At the same time, the closed end of the resonating member has the effect of "covering" those sounds which would otherwise blare out. And I find that the resonating or amplifying effect is present over a wide range of sound pitch and tone quality.

Now another feature of the general arrangement herein illustrated and described 95 is the feature which eliminates loose joints between the vibratory parts of the reproducer and the tone arm. In the usual phonograph construction, there are comparatively loose connections between these two parts; and the looseness causes a certain amount of 100 loose vibration, introducing into the final 105

reproduced sounds a great many undesirable noises. The construction herein shown and described, as will be understood from the foregoing description, is very simple and involves only one tight movable joint between the reproducer and the tone arm, that movable joint being the one about which the reproducer is turned about a horizontal axis. The joint of the reproducer itself to the elbow 22, although it is removable, is also tight, as it is not ordinarily moved from time to time. Furthermore, in my particular form of reproducer herein illustrated, (and which is the subject-matter of my application, Serial No. 359,725, filed February 18, 1920, for phonograph reproducer) the mounting neck 30 which is mounted on the elbow 22 is formed as an integral part of the member which also forms the vibrating diaphragm 31. In fact, through this method of mounting, the vibrating diaphragm 31 becomes the supporting means for the case parts of the reproducer R. The case of this reproducer carries the primary diaphragm 32, which is mounted substantially parallel to and close to the secondary diaphragm 31. On the opposite side of the primary diaphragm 32 there is an enclosed resonating space 34 whose proportions are gaged and designed so as to form an air resonating chamber to resonate and qualify the vibrations of primary diaphragm 32. Primary diaphragm 32 is vibrated through the medium of needle arm 35 from the needle 36. The mounting of the needle need not be herein specifically described. The feature which I wish to bring out in relation to the reproducer is that there are no loosely movable parts in the system between the vibrating parts of the reproducer and the forward end of the tone arm.

In Fig. 3 there is shown a somewhat modified form of the tone arm in which the reproducer makes connection directly into the side of the front end of the tone arm instead of into the end. Here in Fig. 3 a straight nipple 22^a replaces the elbow 22, this straight nipple extending through the wall 26 of resonating tube 21 and also through the wall 40 of the swivel member 41 which forms a swiveling extension of shell 20^a. Extension 41 is mounted tightly but revolubly on shell 20^a and a pin and slot arrangement at 23^a limits the swiveling movement to the same quarter revolution as hereinbefore explained. The tubular sound modifying member is mounted in member 41 and in this case turns with the member 41 when the reproducer is turned for raising or lowering.

Having described a preferred form of my invention, I claim:

1. In apparatus of the character described, a tubular outer shell, and a tubular

sound modifying member extending freely 65 longitudinally through the outer shell and substantially concentric therewith, and defining an annular space between it and the outer shell, said tubular sound modifying member having an open end within said 70 outer shell and said open end being somewhat choked.

2. In apparatus of the character described, a tubular outer shell, and a tubular sound modifying member extending freely 75 longitudinally through the outer shell and substantially concentric therewith, and defining an annular space between it and the outer shell, said tubular sound modifying member 80 being longitudinally slotted through its wall with a plurality of slots circumferentially spaced from each other.

3. In apparatus of the character described, a tubular outer shell, an inner tubular sound modifying member extending lengthwise through the shell and supported in the shell at one end only, the remainder of the sound modifying member being spaced from the inner wall of the shell to define an annular space between it and the shell, the free end of the sound modifying member being somewhat choked but otherwise open to the interior of the shell, and the wall of the sound modifying member being slotted with a plurality of longitudinal circumferentially spaced slots extending from a point near one end to a point near its other end.

4. In apparatus of the character described, a tubular outer shell, and a tubular sound modifying member extending freely 100 longitudinally through the shell and defining an annular space between it and the outer shell, said tubular sound modifying member having an open end within the shell 105 and said end being somewhat choked, and the wall of the tubular sound modifying member being longitudinally slotted.

5. In apparatus of the character described, a tubular outer shell, and a tubular sound modifying member extending freely 110 longitudinally through the shell and defining an annular space between it and the outer shell, said tubular sound modifying member having an open end within the shell, and the wall of the tubular member being slotted with an elongated slot longitudinal of the member.

6. In apparatus of the character described, a tubular outer shell of metal and having relatively thick and heavy walls, and a tubular sound modifying member extending freely longitudinally within the shell and composed of a non-metallic substance.

In witness that I claim the foregoing I have hereunto subscribed my name this 31st day of January, 1921.

ALFRED K. MILLER.
